UNITED STATES PATENT OFFICE.

JOHN WILLIAM NASMITH, OF MANCHESTER, ENGLAND.

WIRE-STITCHING MACHINE.

1,371,388.

Specification of Letters Patent.

Patented Mar. 15, 1921.

Application filed September 9, 1919. Serial No. 322,767.

To all whom it may concern:

Be it known that I, JOHN WILLIAM NASMITH, a subject of the King of Great Britain, residing at Leegate, Heaton-Mersey, Manchester, England, have invented new and useful Improvements in Wire-Stitching Machines, of which the following is a specification.

This invention relates to improvements in wire-stitching machines, and more particularly to the type of machine in which the size of the staple is fixed when the machine is constructed and cannot afterward be altered. In such machine it is usual to cause the whole staple-forming head to descend and nip the material on a stationary anvil, and during this descent the feed is made. The head then remains stationary while the forming bar bends the staple and the driver drives it home, and means, usually in the form of a cam, are employed to hold the head or the forming-bar down during the operation of driving, and in order to allow for small variations in the thickness of the material, arrangements are made to raise or lower the whole head and its mechanism. Also in such machines the head or the forming-bar remains down, clamping the material on the anvil until the driver has risen some distance after completing the driving of the staple, and prevents the operator from immediately displacing the material to position it for the next stitch. It is desirable to make the brief time available for this displacement as long as possible. Finally it has not been usual in such machines to provide a support for the legs of the staple while it is being driven.

The objects of the present invention are to simplify the mechanism by dispensing with the movement of the head, by using a single cam and lever to operate the staple-driver, and mounting on the end of the lever suitable means to operate the staple-former, to combine with such means a "frog" or support for the staple while it is being driven, and to so arrange the mechanism that the frog, the staple-driver, and the staple-former shall all rise together and release the material the moment the driving of the staple is completed.

These various points will now be described in detail with reference to the drawing, in which—

Figures 1 and 2 are side and end ele-

vations respectively, of the machine when at rest before the stroke commences.

Figs. 3 and 4 are side and end elevations respectively, of the machine showing position of the parts at the moment the driving of the staple is completed.

Fig. 5 shows a small detail of the machine.

I will now describe my device, referring to the drawings in detail by reference numerals, the same numerals designating the same parts throughout the drawings.

A represents an anvil, which is mounted for vertical adjustment on an arm R, adjustment being accomplished through the medium of an adjusting-screw 30, or by any other suitable means. The arm R is provided at its upper end with a horizontally extending portion in parallelism with the anvil A, and having formed on its outer end a head H. Pivotedally mounted intermediate of its ends on an upwardly projecting extension of arm R, by means of the fixed stud S, is a lever L, having one end connected to a cam C by means of a pin 1, on which is mounted a roller B, adapted to ride in an irregular slot or groove M formed in the cam, the opposite end of the lever being connected with a driver D slidably mounted in the head H. The cam is mounted for rotation about a stud P, fixed to the arm R, and has a projecting cam surface 3 on one edge thereof. Pivoted to the cam C by means of a pin 2 is a connecting-rod O, to the lower end of which may be connected a treadle, a power device, or any other suitable means, for actuating said rod, and thereby turning the cam C on its pivot. The groove or slot M in cam C has a portion M'', which is curved on the arc of circle substantially concentric with the pivot P and a portion M' eccentric thereto for a purpose which will presently appear.

Pivotedally mounted at 31 on the arm R is a lever 5, to one end of which is pivotally attached a rod 33, at the forward end of which is carried a suitable means for feeding wire. This feeding means may be of any of the usual types well known in the art, and is omitted inasmuch as it constitutes no part of the present invention. The upper end of lever 5 is connected to arm R through the medium of a contractile spring 34, by which the rod 33 is normally held retracted. Extending from the lever between the pivot points 31, and 32 is a pin on which

the roller 4 is mounted, said roller being adapted to press at all times against the edge of the cam C.

As the cam C moves from the position shown in Fig. 1 to that shown in Fig. 3, the roller B rides in the circular path and the lever L receives no motion, while at the same time the roller 4 rides on the projecting cam surface 3 moving lever 5, against the force of spring 34 and effecting the feed. Simultaneously with the completion of the feed, the roller B begins to ride in the inclined eccentric portion M² of the slot, driving the roller B upward and rocking the lever L, forcing the driver D downwardly.

Cast on the under side of the lever L are two projections 6 and 7, apertured to receive a rod 8, on the outer end of which is a block 9, arranged to rest against and slide on a finished face 10, on the under side of the lever. The outer face of the block 9 is inclined downwardly and rearwardly as shown at 11, for a purpose which will appear later. On the rod 8 is fixed, in a suitable position, a collar 12 and a spiral spring G is placed in compression between the collar and the projection 7, which forces the rod 8 and block 9 outwardly, until arrested by the adjusting nuts 13 abutting against the projection.

A staple-former F is slidably mounted in a groove formed in the head H, and is itself grooved to receive the driver D, which is provided with an inclined surface 14, formed on the inner vertical face thereof.

The under face of the block 9 rests on the upper end of the staple-former F until, as the lever L descends, describing an arc of a circle with the stud S as center, it is drawn off the top of the staple-former, which moves tangentially to the said arc, and thereupon the staple-former F ceases to be driven positively downward. The moment at which this occurs can be regulated by means of the adjusting nuts 13 to happen just as the material is clamped between the bottom of the staple-former F and the anvil. In order that the staple-former may be held firmly down on the material while the staple is being driven by the continued descent of the driver D, the inclined face 11 of the block 9 is forced down the inclined face 14 at the top of the staple-former, against the force of the spring G, which is further compressed so that the staple-former is firmly held down on the material, notwithstanding its tendency to rise under the influence of the spring Z, as will now be described.

Spring Z is attached to one end of a lever 15 pivoted at 15^a on the head H, having an arm 15^b which projects below a roller 16, carried on a pin 17 fixed in a pendant 18, to be described. The other end of the spring Z is attached to the lower end of a lever 19 which swings on a fixed pin 20,

extending from the head H, and presses a roller 21 carried on the lower end thereof firmly against the back of the pendant 18, thus tending to hold a suitably formed frog or support X projecting from its lower extremity in the forked lower end of the staple-former F, and consequently between the legs of the staple, whence it is forced out by the descending driver as the staple is being driven. The upper end of the pendant 18 is formed with a slot 22 engaged on a pin 23, fixed in the staple-former F.

Cast upon the pendant 18 is a projection 24 which is normally held by the tension of spring Z acting through lever 15, and tending to raise pendant 18, against pin 20 by which the upward movement of the pendant is limited. The staple-former F, however, is free to be raised further, and is limited only by the upper end of the slot 22, and is raised by means of a pin 25 formed thereon which fits in slot 26 formed in the driver D when the lower limit of said slot comes in contact with said pin, the driver and former again ascends together until the pin 23 reaches the upper limit of slot 22.

When the staple-former F commences to descend with the driver D from the position shown in Fig. 1, the pendant 18 does not move with it until the pin 23 contacts with the bottom of the slot 22. All three then descend together until the former F clamps the material against the anvil. At this moment the block 9 slips off the top of the staple-former F and the continued descent of the driver D forces the incline 11 down the incline 14, as already described, notwithstanding the spring Z. When the driver is no longer moving downward, but on the contrary, begins to rise, the staple-former F and the pendant 18 rise with it, since the force of the spring G is not so overpowering as to keep the staple-former F down, unless assisted by the friction of the descending lever L, forcing the incline 11 down the incline 14. Therefore, all three rise together and release the material immediately the driving of the staple is completed. They continue to rise together until the upward movement of the pendant 18 is arrested by the projection 24 coming against the pin 20. The staple-former F also ceases to rise (since spring Z has ceased to act on it) until the continued rise of the driver D brings the bottom of the notch 26 against the pin 25, whereupon, the staple-former F accompanies the driver D for the remaining portion of the upward stroke, the block 9 having meantime resumed its position between the top of the staple-former F and the lever L.

By these means a simple cam and lever serve to make the feed operate the staple-former and driver in the proper manner,

and operate a support for the staple legs while the staple is being driven, and cause the staple-former to rise with the driver and give the operator the maximum possible 5 time to position the material for the next stroke.

It is sometimes required to have the anvil 10 A very long, and the arms of the lever become correspondingly long. In such cases the are described by the block 9 approximates to a straight line, and it becomes difficult by means of the nuts 13 to adjust precisely the moment when the block 9 slips off the top of the staple-former F, so as to 15 coincide with the clamping of the material. Several means may be devised to effect this at the required moment. One such means is shown in Fig. 5. A suitably shaped piece 27, is carried by and adjustable on the 20 framing and a projection 28 is formed on the collar 12, and abuts against the back of the lever L to prevent turning. This projection comes in contact, at the required moment, with the incline 27, which is so formed 25 that, having forced the block 9 off the top of F, it no longer contacts with the projection 28, but allows the incline 11 to press against the incline 14, as shown in Fig. 3.

I claim:—

30 1. In a wire-stitching machine, a stationary head, a staple-former and a driver slidably mounted in said head, an anvil extending beneath said head, a cam and lever for operating said staple-former and driver, means on the end of the lever to force the 35 staple-former positively downward until a staple has been formed and clamped on said anvil and to hold it down while the driver descends to drive and clench the staple and 40 means whereby the staple-former and driver commence their ascent simultaneously the moment the driving and clenching of the staple is completed.

2. In a wire-stitching machine, a stationary head, a staple-former and a driver slidably mounted in said head, an anvil extending beneath said head, a cam and lever for operating said staple-former and driver, means on the end of the lever to force the 50 staple-former positively downward until a staple has been formed and clamped on said anvil and to hold it down while the driver descends to drive and clench the staple and a pendant attached to said staple-former, spring-pressed upwardly whereby the staple-former is raised simultaneously with the driver when the driving and clenching of the staple are completed and the driver starts upwardly.

55 3. In a wire-stitching machine, a stationary head, a staple-former and a driver slidably mounted in said head, an anvil extending beneath said head, a cam and lever for operating said staple-former and driver, means on the end of the lever to force the

staple-former positively downward until a staple has been formed and clamped on said anvil and to hold it down while the driver descends to drive and clench the staple and a pendant attached to said staple-former having 70 a frog extending therefrom to support said staple-former, said pendant being spring-pressed upwardly whereby the staple-former is raised simultaneously with the driver when the driving and clenching of the staple are completed.

4. In a wire-stitching machine, a stationary head, a staple-former and a driver slidably mounted in said head, an anvil extending beneath said head, a cam and lever for 80 operating said staple-former and driver, means on the end of the lever to force the staple-former positively downward until a staple has been formed and clamped on said anvil and to hold it down while the driver 85 descends to drive and clench the staple, resilient means tending to raise said staple-former when so held down whereby when the driver starts to rise the staple-former will rise simultaneously therewith. 90

5. In a wire-stitching machine, a stationary head, a staple-former and driver slidably vertically in said head, an anvil extending beneath said head, a cam and lever for operating said staple-former and driver, a 95 spring controlled rod on the under side of said lever having a block on its outer end, said block being adapted to rest on the upper end of said staple-former and to force it positively downwardly in said head into 100 position to clamp staple-forming material on said anvil when the lever is operated, said staple-former being provided at its upper end with a rearwardly and downwardly beveled surface, a corresponding surface on 105 the forward end of the said block, the relation of the parts being such that when said former has reached a position to grip said material the block will slide off the top of said former and the beveled faces will coöperate to hold the former in gripping position while the driver descends to drive the staple. 110

6. In a wire-stitching machine, a stationary head, a staple-former and driver slidably vertically in said head, an anvil extending beneath said head, a cam and lever for operating said staple-former and driver, a spring controlled rod on the under side of said lever having a block on its outer end, 115 said block being adapted to rest on the upper end of said staple-former and to force it positively downwardly in said head into position to clamp staple-forming material on said anvil when the lever is operated, 120 said staple-former being provided at its upper end with a rearwardly and downwardly beveled surface, a corresponding surface on the forward end of said block, the relation of the parts being such that when 125 130

said former has reached a position to grip said material the block will slide off the top of said former and the beveled faces will co-operate to hold the former in gripping position while the driver descends to drive the staple, and means whereby the staple-former and driver commence their ascent simultaneously the moment the driving and clenching of the staple is completed.

7. In a wire-stitching machine, a stationary head, a staple-former and a driver slideable vertically in said head, an anvil located below said head, a cam and lever for operating said former and driver, a spring controlled block on the under side of said lever, said block being adapted to rest on the upper end of said staple-former and to force it positively downwardly in said head into position to clamp staple-forming material on said anvil when the lever is operated, said staple-former being provided at its upper end with a rearwardly and downwardly beveled surface, a corresponding surface on the forward end of said block, the relation of the parts being such that when said former has reached a position to grip said material, the block will slide off the top of said former and the beveled faces will co-operate to hold the former in gripping position while the driver descends to drive the staple.

8. In a wire-stitching machine, a stationary head, a staple-former and driver slideable vertically in said head, an anvil extending beneath said head, a cam and lever for operating said staple-former and driver, a spring-controlled rod on the underside of said lever having a block on its outer end, said block being adapted to rest on the upper end of said staple-former and to force it positively downwardly in said head into position to clamp staple-forming material on said anvil when the lever is operated, said staple-former being provided at its upper end with a rearwardly and downwardly beveled surface, a corresponding surface on the forward end of said block, adjusting nuts on said rod whereby the relation of said block to said former may be regulated so that the block will slide off the top of said former when the lower end of the former has reached a position to grip staple-forming material in said anvil, and the beveled faces will co-operate to hold the former in gripping position while the driver descends to drive the staple.

9. In a wire-stitching machine, a stationary head, a staple-former and driver slideable vertically in said head, a cam and lever for operating said staple-former and driver, an apertured projection on the underside of said lever, a rod reciprocally mounted in said lugs, a block on the forward end of said rod, slideable against the under surface of said lever and adapted to rest on the up-

per end of said staple-former and to force it downwardly into position to clamp staple-forming material on said anvil when the forward end of the lever descends, said block and said staple-former being provided with complementary sloping faces, a collar on said rod and a compression spring between said collar and one of said projections for forcing said block forward, adjusting nuts screwthreaded on said rod whereby the tension of said spring may be adjusted so that the block will slide off the top of said former and onto the inclined surface of the former, at the time it contacts with the staple-forming material and means to adjust the tension of said spring sufficiently to hold said former in clamping position while the driver descends to drive the staple.

10. In a wire-stitching machine, a stationary head, a staple-former and driver slideable vertically in said head, an anvil extending beneath said head, a cam and a lever for operating said staple-former and driver, and apertured lugs on the under side of said lever, a rod reciprocally mounted in said lugs, a block on the forward end of said rod, slideable against the under-surface of said lever and adapted to rest on the upper end of said staple-former and to force it downwardly into position to clamp staple-forming material on said anvil when the forward end of the lever descends, said block and said staple-former being provided with complementary sloping faces, a collar on said rod and a compression spring between said collar and one of said projections for forcing said block forward, adjusting nuts screwthreaded on said rod whereby the tension of said spring may be adjusted so that the block will slide off the top of said former and onto the inclined surface of the former, at the time it contacts with the staple-forming material and to adjust the tension of said spring so as to regulate the force with which the block is forced against the inclined surface on the former.

11. In a wire-stitching machine, a head, an anvil therebeneath, a cam and a lever and supporting means therefor, a former and a driver slidably mounted in said head, said former being adapted to be brought into position to clamp staple-forming material on said anvil, a spring pressed block slidably mounted on the lower side of said lever and adapted to rest on the top of said former while the former moves into clamping position, an inclined surface on said former, a correspondingly inclined surface on said block, means for sliding the block off the upper end of said former onto said inclined surface when the former has reached clamping position.
